UNITED STATES PATENT OFFICE.

JOHN O. MONTIGNANI, OF ALBANY, NEW YORK, ASSIGNOR TO A. TWINER.

IMPROVED CLOTHES-RACK.

Specification forming part of Letters Patent No. **59,133**, dated October 23, 1866.

To all whom it may concern:

Be it known that I, JOHN O. MONTIGNANI, of the city of Albany, State of New York, have invented a new and useful Improvement in the Construction of Portable Clothes-Racks, of which the following specification, with the drawings forming part thereof, is a full and accurate description.

The kind of portable clothes-rack above referred to consists of an oblong frame of wood, made of two horizontal rails connected together by two perpendicular shorter rails fastened to the other rails at their ends, and carrying between them a number of metal clothes-pins.

Figure 1 exhibits a portion, being one of the ends of a frame with one of the clothes-pins attached.

However well these rails may be doweled or otherwise fastened to each other with wooden fastenings, (metal angle-pieces or other fastenings are too costly,) they are at best weak structures, and liable to be separated by the pressure of the usual load upon the pins, if they (the pins) are made and fitted in the ordinary way.

The object of my invention is to construct the pins in such manner as to make them assist in holding the rails together without adding to the cost of construction of the rack. This I do simply by making an alteration in the pivot or axle part of the pin.

The ordinary pin has its ends formed into cylindrical or tapering pivots, as shown at A, Fig. 2, so as to allow it to be turned in between the rails when not needed for service. Such pivots, it is manifest, would, without any resist-

ance, be drawn out of their sockets should the frame be broken.

My improvement consists in giving to the extremities of the pivots an outward swell with a tapering or rounded head, leaving a short neck next the stem of the pin, as shown in B, Fig. 1, where a portion of the wood is shown cut away to exhibit the form of the pivot and its socket. This socket is bored out in the rail to only the size of the neck or narrowest part of the pivot, and when the frame is put together the pivots are forced into their sockets. The result of this will be that after the swelled head of the pin has passed the outer part of the bore the wood which has been compressed by it will expand and surround the neck so firmly that it will require as much force to withdraw the pin from the wood as it did to drive it to its place—in fact, so firmly that if there were no end-pieces to the frame the weight of ordinary heavy garments upon the pins could not draw them from their sockets.

This improvement of the pins adds no expense to the construction of the racks described, while it makes a better because stronger and more durable article.

What I claim as my invention, and desire to secure by Letters Patent, is—

The construction of clothes-pins for portable clothes-racks by forming their axes or pivots as described.

J. O. MONTIGNANI.
